Erastus S. Root

Gallows Patent

301

9665X.

The defendant appears to be in these Gallows Patent and making part of the same containing a description in the words of the said Erastus S. Root himself of his improvement in the Horse Rake for Hay or Grain.

To all to whom this presents shall come—

Be it known that Erastus S. Root of the town of Mount Morris County of Livingston and State of New York have invented a new and useful improvement in the Horse Rake for Hay or grain and that the following is a full and exact description thereof. The said Rake is to be twelve feet in length. The teeth of wood and about three feet long, said rakes to be attached either to a scythe or scythes and to be built as follows. The head of said rake to be formed of two strong pieces parallel with each other about eighteen inches apart. said pieces to be framed into other pieces at the ends. said Rake is to be raised by two levers about ten feet in length, framed into the strong pieces, or lower pieces and made permanent by braces from the levers to the strong pieces. said levers to enter the strong pieces about three feet from each end and to be fastened to the axle tree of the carriage, or a piece of timber lying along the same in the following manner:

1st By dry hills near the shoulder of the axle tree and about the center of the levers, or by boring holes through the levers and slipping them on the ends of the axle tree outside of the hubs, or if on a narrow log slipping the levers on the ends of the timber lying along the same. Carriage to be built after the manner of ordinary carriages, or said Rake can be attached to any carriage. The person making use of Rake stands upon ^{the} first part of the carriage and manages the

1065

the rake by a clip piece on the end of the lever which gives the individual complete control over the raker without its noise. Is it to hold it down by means of the lever. What I claim as my own invention is the before mentioned rake and not previously known is the manner of raising the rake and also the manner of attaching it to wheels or carriage, or any other carriage, said rake being so constructed as that it may be attached to the fore wheels of a one-horse waggon.
